UNITED STATES PATENT OFFICE.

CLARENCE HAYDOCK, OF SAN FRANCISCO, CALIFORNIA.

BINDER.

1,177,411.

Specification of Letters Patent. Patented Mar. 28, 1916.

Application filed February 13, 1915. Serial No. 8,041.

To all whom it may concern:

Be it known that I, CLARENCE HAYDOCK, citizen of the United States, residing at San Francisco, in the county of San Francisco and State of California, have invented new and useful Improvements in Binders, of which the following is a specification.

My present invention pertains to temporary binders, and consists in the simple, inexpensive, easily manipulated and highly efficient binder for holding punched and unpunched leaves, pamphlets, railroad tariffs, directories and other books, as hereinafter described and definitely claimed.

15 In the accompanying drawings which are hereby made a part hereof: Figure 1 comprises disconnected perspectives of parts of one binder constructed in accordance with my invention, the covers being partly broken 20 away. Fig. 2 is a section taken through the covers and in front of the back. Fig. 3 shows a portion of a punched leaf designed to be held in my binder. Fig. 4 is an enlarged transverse section of the binder. Fig. 25 5 is a front elevation, partly in section and partly broken away, of a modification. Fig. 6 is a plan of the back thereof. Fig. 7 is a section on line 7—7 of Fig. 5. Fig. 8 is a detail plan of the retaining member. Fig. 30 9 is a section on line 9—9 of Fig. 5, showing in use the device for attaching to the binder unpunched leaves, pamphlets and the like. Fig. 10 is a transverse section of the punching device (Fig. 12). Fig. 11 is a detail 35 plan of the said attaching device. Fig. 12 is a detail view showing a punching device on one of the walls of the binder back.

Referring by numeral to the said drawings, and particularly to Figs. 1 to 4 there- 40 of: 1 is the back of my novel binder, which may be made of sheet metal or any other material compatible with its purpose. The said back comprises a back wall, upper and lower walls or side walls, and end walls, as 45 clearly appears in Fig. 1. Hinged to one side wall of the back is a cover 2, and flexibly connected with the back through a longitudinally-disposed link 3, Figs. 1 and 4, is the opposite cover 4. The bar of the link 50 3 opposite to that in the barrel or barrels 5 of the cover 4 and the barrel or barrels 6 on the lower side wall of the back 1 is arranged in the bight of a sheet-metal strip, as indicated by 7 in Fig. 4. The said sheet- 55 metal strip is numbered 8, and by reason of the construction described is strongly held

in position on the lower side wall of the back 1. In the upper wall of the bent strip 8 socket apertures 9 are provided for a purpose hereinafter set forth, and fixed to and 60 extending upwardly from the said strip 8 are pins 10, best shown in Fig. 1. Fixed at the underside of the upper side wall of the back 1 is a strip 11 having a lip 12 at its forward edge, and designed to be remov- 65 ably-retained in position by the said lip 12 is a retaining device 13. This device 13 is preferably formed of sheet-metal, bent upon itself, and is provided in its lower wall with socket apertures 14 to receive the pins 10, 70 and is also provided with pins 15, designed to be seated in the socket apertures 9 of the strip 8.

In the practical use of the embodiment just described, leaves, such as shown in Fig. 75 3, are impaled on the pins 10, after which the pins 15 are passed through the inner apertures of the leaves, and the retaining device 13 is sprung behind the lip 12 and thereby confined in the position shown in 80 Fig. 4. Incidental to the described placing of the retaining device 13, the upper side wall of the back 1 is sprung outwardly by the operator drawing on the cover 2 that is connected to said side wall, and this is also 85 done when it is desired to remove the retaining device 13 from its position behind the lip 12. It will also be noticed in this connection that incidental to the impalement of the leaves on the pins 10, the strip 8 90 can be swung forwardly so as to facilitate the impalement of the leaves on the pins 10, as well as the placing of the pins 15 in the apertures of the leaves and the socket aper- 95 tures 9 of the strip 8, and the placing of the strip 13 in engagement with the pins 10. The said positioning of the strip 8 and the pins 10, is clearly shown in Fig. 1 and it will be manifest that after the leaves and the retaining device 13 are properly placed 100 relative to the strip 8 and the pins 10, the connected strips 8 and 13 can be swung back into the back 1, and the strip or retaining device 13 confined behind the lip 12, as before described.

105 It will be gathered from the foregoing that the construction described is easy to manipulate and yet is calculated to effectually prevent the casual disconnection of any leaf that is properly engaged with the pins 10 110 and 15. At this point I would have it understood that when desired the apertured holder

16 shown in Figs. 5, 7, 9 and 11 of the drawings, may be employed in combination with the embodiment shown in Figs. 1, 2 and 4. The said holder 16 may be made of light sheet-metal or other suitable material and is provided with inwardly reaching arms 17 designed to be placed in the bight of a folded pamphlet or leaves, after the manner shown in Figs. 7 and 9. Manifestly, the holder engaged with pamphlet or leaves in the manner described is adapted to be impaled on the pins 10 and to receive the pins 15 of the retaining device 13 comprised in the binder shown in Figs. 1, 2 and 4.

15 The modified construction shown in Figs. 5 to 9 is similar in principle to the embodiment shown in Figs. 1, 2, and 4, and differs from the latter only in details of construction as will now appear. The back 1^a of the modification is provided on its upper side wall with lips 12^a, and the upper cover 2 of the modification is connected to the forward edge of the side wall in any approved manner. The opposite cover 4 is connected 20 to the lower side wall of the back in any approved hinged manner. The lower side wall of the back 1^a is provided with bearings 18, and in the said bearings are journaled trunnions 19 at the opposite ends of a channeled strip 20 to which pins 21 are fixed. By virtue of this construction the strip 20 and the pins 21 are adapted to be swung forwardly, relative to the back, so that either leaves or the holder 16 can be expeditiously and easily 25 impaled on the pins. The retaining device 13^a, for use in combination with the back 1^a and the pins 21, comprises a lower bar 22 having apertures 23 to receive the pins 21 and also having upwardly extending guide-pins 24, an upper bar 25 having apertures 26 to receive the pins 24, and a bowed spring 27 interposed between the bars 22 and 25 and held by certain of the guide-pins. It will also be noticed that the lower bar 22 of 30 the retaining device is provided with depending pins 28, the lower ends of which are adapted to be seated in the channeled strip 20, as clearly appears in Fig. 9.

The general operation of the modification is similar to that of the embodiment shown in Figs. 1, 2 and 4, with the exception that the modified retaining device 13^a is adapted to be compressed against the action of the bowed spring, so as to permit of 35 said retaining device being moved past the lips 12^a, when the pins and retaining device are swung into the back. Obviously this does away with the necessity of springing the side wall of the back outwardly as described with reference to the embodiment in Figs. 1, 2 and 4.

As clearly appears in Figs. 5, 7 and 9, the holder 16 hereinafter described is designed to be used to advantage in combination with the modified construction, but it

is to be understood that the modified construction is equally capable of engaging and holding punched leaves. When desired the upper cover 2 of the modification can be equipped with a leaf punching device, as shown in Figs. 10 and 12. The said device comprises an upper bar 25^x hinged to said cover 2 and having apertures 26^x near its free edge to receive punching pins 24^x on a lower bar 22^x Fig. 10, and also having smaller apertures 26^b to receive guide pins 24^b on said lower bar, and a spring 27^x interposed between and connecting the bars 25^x and 22^x and serving to yieldingly hold said bars in spaced relation as illustrated in Fig. 10. 80

When it is desired to punch holes in leaves, pamphlets, etc., to adapt the same for impalement on the pins 21 and 28, it is simply necessary to interpose the leaves or pamphlets between the pins 24^x and the upper bar 25^x and force said upper bar downwardly. It will be noted further that the construction shown in Figs. 10 and 12 is further advantageous inasmuch as it is carried by the cover 2 and forms a permanent part of the binder, and is therefore always at hand when it is desired to put it into use. The upper bar 25^x of the punching device may have its edge opposed to and hinged directly on the edge of the cover 2, or, if preferred, the cover 2 may have a thin metal plate riveted or otherwise secured thereon, and the bar 25^x may be hinged directly to the said plate.

Having described my invention, what I claim and desire to secure by Letters Patent, is:

1. The combination in a binder, of a back having a back wall and side and end walls and also having a lip on one of its side walls, a swinging strip having a pin and also having a socket aperture, a cover, a longitudinally-disposed link having a bar connected to the other side wall of the back and the cover and also having a bar connected to the said strip, and a retaining strip constructed to be yieldingly and removably held behind the lip of the back and having a socket aperture and also having a pin arranged to enter the socket aperture of the swinging strip.

2. The combination in a binder, of a back having a back wall and side and end walls and also having a lip on one of its side walls, a swinging strip hinged to the other side wall of the back and movable into and out of the same and having an impalement pin and also having a socket, and a retaining strip constructed to be yieldingly and removably held behind the lip of the bracket and having a socket aperture and also having an impalement pin arranged to enter the socket of the swinging strip.

3. A binder comprising a back, a cover thereon, impalement pins carried by the

back, and a punching device made up of two bars; the edge of one bar being hinged to the opposed edge of the cover, and one bar being movable bodily toward and from the other, and one bar being provided with pins the same distance apart as said impalement pins and the other bar being provided with apertures to receive the bar pins.

4. A binder comprising a back having a back wall and side and end walls and also having a lip at the inner side of one side wall and bearings on the inner side of the other side wall, a channeled strip having trunnions at its ends journaled in said bearings and also having an impalement pin,

and a retaining device constructed and arranged to be compressed and to be confined in the back behind the said lip thereof and having an aperture to receive the pin of the channeled strip and also having a pin the 20 end of which is arranged to rest in the channel of said strip.

In testimony whereof I have hereunto set my hand in presence of two subscribing witnesses.

CLARENCE HAYDOCK.
